UNITED STATES PATENT OFFICE.

WILLIAM RUFUS JONES, OF SUMMITVILLE, INDIANA.

HEATER.

1,408,743.

Specification of Letters Patent.

Patented Mar. 7, 1922.

Application filed August 14, 1920. Serial No. 403,537.

To all whom it may concern:

Be it known that I, WILLIAM RUFUS JONES, a citizen of the United States, and a resident of Summitville, in the county of 5 Madison and State of Indiana, have invented certain new and useful Improvements in Heaters, of which the following is a specification.

The present invention relates to improvements in heaters.

The object of the invention is to provide an improved heater which will efficiently radiate the heat generated by the combustion of solid, liquid or gaseous fuel, which 15 is easily controlled, and which is of simple and durable construction, reliable in operation, and easy and inexpensive to manufacture.

Other objects and advantages of the invention reside in certain novel features of construction, combination and arrangement of parts as will be hereinafter more fully described and particularly pointed out in the appended claims, reference being had to 25 the accompanying drawings forming part of this application, and in which:

Figure 1 is a transverse vertical sectional view of the heater, parts being shown in elevation for the sake of illustration;

Figure 2 is a plan view;

Figure 3 is a transverse horizontal section thereof on line 3—3 of Figure 1;

Figure 4 is a fragmentary front elevational view;

Figure 5 is a fragmentary detail view.

Referring to the drawings wherein is shown the preferred embodiments of the invention and especially to Figures 1 to 5, the base of the heater is indicated at A, the 40 ash pit at B and the fire box or fire pot at C. These parts are in general of conventional construction. The fire box or fire pot is adapted to initiate combustion and to utilize either solid, liquid or gaseous fuel. 45 At its upper end the fire-box is provided with an outwardly flared portion c having a plurality of laterally and inwardly extending wings 5 which serve to support parts of the heater as will be hereinafter 50 more fully described.

The heater comprises a cylindrical casing 6 having a closed top 7 and an open lower end which is secured to and carried by the flared portion c of the fire box. A 55 reinforcing plate 8 is secured to the front of the casing and this reinforced portion

of the casing carries an upper door 9 and a lower door 10. The top 7 of the casing is provided with a flue pipe connection 11. Adjacent the lower end of the casing is provided a curved guard rail 12 and a similar guard rail 12^a is provided adjacent the upper end of the casing.

A drum 13 is arranged within the casing coaxially thereof and is provided with a 65 relatively large number of widely distributed lateral discharge openings 14. The top wall of the drum may also be provided with a single circular series of discharge openings 15 but it is to be understood that the 70 number and dimensions of the openings 15 are such that the main discharge is constrained to flow laterally through the discharge openings 14. The drum being arranged coaxially of the casing there is defined between the outer wall of the drum and the inner wall of the casing a heating chamber designated at 16. The top wall of the drum may also be provided with a smoke opening 17 having a sliding closure 18 operated by a pull rod 19. The closure 18 normally covers the smoke opening 17 and it is only when the doors 9 and 10 are open that this closure is moved to uncover the opening 17 to permit free outlet of all smoke through 85 the flue pipe and preclude any possibility of the smoke or heat discharging through the open doors. Adjacent the doors 9 and 10 the drum 13 is open and is extended and secured to the outer casing, as designated 90 at 13^a.

Air feeding, heating and distributing means is provided, and consists of two substantially arcuate ring sections 20, each of which is identical in construction, arrangement and function. They are arranged beneath and secured to the perforated drum 13 by means of upstanding lugs 20^b and fastening means 20^c and support the drum. The ring sections themselves are supported upon 100 the wings 5 by means of lugs 21 and fastening means 21^a. The opposite vertical walls of each of the hollow semi-annular sections have a plurality of vertical slots or openings 22 arranged throughout the circumferential 105 extent and extending from the top to approximately midway each vertical wall. The top and bottom walls as well as the lower portion of the vertical walls are imperforated. An imperforate semi-circular 110 partition 23 is arranged interiorly of each semi-annular ring section and separates the

upper perforate portion from the lower imperforate portion and thereby defines an upper chamber designated at 24 and a lower chamber designated at 25. The lower chamber of each ring section is provided with an opening 26 to provide for the intake of air into the lower chamber and at the other end of the ring the lower chamber is closed except for a port 27 provided in the partition 10 23 which constitutes an outlet for the air, then heated, to the upper chamber 24 in which it is further heated and discharged through the slots of the opposite vertical walls to the opposite sides of the perforated drum. Both ends of the upper chamber are closed, as indicated at 28.

A common air inlet is provided for both of the semi-annular ring sections. This air inlet comprises a three-part casting 29 bolted 20 to the casing adjacent one of the wings 5 and to the fire pot, as indicated at 30. The parts of the casting embrace the adjacent ends of the ring sections 20 which are for this purpose each provided with a marginal 25 flange 20^a, as shown in detail in Figure 5. The inlet chamber is provided with an air inlet opening 31 which is adapted to be controlled by a closure plate or valve 32 carried by the threaded shank 33 of an operating handle 34. The threaded shank 33 is journaled in a corresponding opening of the depending lug 35 carried by the upper part 30 of the casting.

If desired a feeding magazine 37 for supplying fuel to the fire pot may be provided, and preferably consists of a tubular body having an outwardly extending flange 37^a at its upper end arranged to rest upon an inwardly extending flange 38^a formed at the 40 lower end of a hopper 38, the upper end of which hopper is provided with an outwardly extending flange 38^b whereby the hopper may be bolted to the exterior casing, as shown in Figure 1.

45 In operation with this form of the invention the products of combustion rise from the fire box and flow upwardly on the opposite sides of the interior drum. The heated air flowing from the slots 22 of the 50 ring sections of the air feeder, heater and distributor encounters these products of combustion when they are not yet completely consumed and completes the combustion thereof so as to liberate all of the heat 55 of the fuel. The heat from the gases on the outside of the drum directly heat the exterior casing and radiates this heat in that way whereas the heat of the gases of combustion on the interior of the drum is carried 60 by these gases directly against the interior of the outside casing as these gases of combustion are projected laterally through the lateral discharge openings of the drum. The gases strike the interior wall of the out- 65 side casing at right angles and thus provide

for the effective transmission or radiation of the heat by the casing much more so than if the heat arising were permitted to glide along the surface or strike the surface at a very small angle.

70

I claim:

1. A heater of the character described, comprising a fire box, a casing supported thereon, a drum arranged within said casing and coaxial thereof, said drum having lateral discharge openings, air feeding, heating and distributing means disposed between the fire box and the drum and consisting of annular ring sections each having an upper perforated portion and a lower imperforated portion, and an imperforate partition arranged therebetween to define an upper and a lower chamber, said lower chamber having an air intake opening and an outlet port to the upper chamber opposite the said intake opening, and an air inlet for said ring sections consisting of a three-part casting embracing said sections and having an air inlet opening, a closure plate for said inlet opening and a threaded operator for said closure plate, and means for supporting said ring sections beneath said drum whereby said upper perforated chamber discharges heated air on opposite sides of said drum.

95

2. A heater of the character described comprising a fire box, a casing supported thereon, a drum arranged in said casing and coaxial thereof, said drum having lateral discharge openings, air feeding, heating and distributing means disposed between the fire box and the drum and consisting of annular ring sections, each having an upper perforate portion and a lower imperforate portion, and an imperforate partition arranged therebetween to define an upper and a lower chamber, said lower chamber having an air intake opening and an outlet port to the upper chamber opposite the said intake opening, and an air inlet for said ring sections consisting of a three-part casting embracing said sections and having an air inlet opening, a closure plate for said inlet opening and a threaded operator for said closure plate.

11

3. In a heater of the character described comprising in combination with a fire box, a casing supported upon said fire box, a drum arranged within said casing and having lateral discharge openings, air feeding, heating and distributing means consisting of semi-annular ring sections disposed between said drum and said fire box and having openings discharging on opposite sides of said drum, and an auxiliary magazine extending centrally of said drum.

12

4. In a heater of the character described, comprising in combination with a fire box, a casing supported upon said fire box, a drum arranged within said casing having

13

lateral discharge openings, air feeding, and heating and distributing means consisting of semi-annular ring sections disposed between said drum and said fire box and having openings discharging upon the opposite side of said drum.

5. A heater of the character described comprising a fire box, a casing, a drum within said casing, an air feeding, and heating and distributing means disposed between 10 said fire box and said drum and arranged to discharge heated air upon the opposite sides of said drum.

6. Air feeding and discharging means for 15 a heater of the character described comprising semi-annular ring sections having opposite vertical walls provided with openings arranged throughout the circumferential extent and extending from the top to approximately midway of the wall, imperforate top and bottom walls, and a circular partition arranged within each ring section 20 and separating the upper perforate portion from the lower imperforate portion to 25 define an upper and a lower chamber, each of said ring sections having an air intake

port to the lower chamber and said circular partition having an outlet port from the lower chamber, to the upper chamber opposite the intake port of said ring sections, 30 and an air intake receiving the intake ends of said ring sections and having manually operable means controlling the inlet of the air.

7. A heater of the character described 35 comprising a fire box having laterally and inwardly extending wings at its upper end, a casing supported upon said fire box, a drum arranged within said casing having lateral discharge openings, air feeding, heating and distributing means disposed between the fire box and the drum and consisting of annular ring sections having openings discharging on opposite sides of said drum, a plurality of depending lugs carried by 40 the under side of said ring sections and disposed adjacent and secured to the respective wings of said fire box, and a plurality of upstanding lugs carried by the upper side of the ring section and disposed 45 adjacent and secured to said drum.

WILLIAM RUFUS JONES.
